UNITED STATES PATENT OFFICE.

CHARLES EDWARD HAVILAND, OF LIMOGES, FRANCE.

DESIGN FOR A DISH.

SPECIFICATION forming part of Design No. 15,630, dated December 16, 1884.

Application filed July 3, 1884. Term of patent 14 years.

To all whom it may concern:

Be it known that I, CHARLES EDWARD HAVILAND, a citizen of the United States, residing in the city of Limoges, Republic of France, have invented and produced a certain new and original Design for Dishes, fully described and represented in the following specification and the accompanying drawings, forming a part of the same.

- 10 In said drawings, Figure 1 is a plan or top view of a platter embodying the design. Fig. 2 is a plan or top view of a large plate, and Fig. 3 a similar view of a small plate, embodying the design. Fig. 4 is a plan or top view 15 of a saucer, and Fig. 5 a side elevation of a cup, embodying the design. Figs. 6 and 7 are respectively a side elevation and perspective view of a covered dish embracing the design.
- 20 In this specification no description is given of what is technically called the "decoration," which consists of the flower-patterns distributed over the surface of the articles, for the reason that such decoration forms no part of the 25 design, and may be varied as fancy may dictate or trade requirements demand.

The design relates to the dishes of a table-service; and it consists in the ornamentation of the surface of the dishes, and generically 30 embraces the peculiar central panel, its border, and the external or edge border, as shown. Said design may be segregated, and either of these ornamentations may be embodied separately and in combination, and still be within 35 the scope of this design. The central panel, A, consists in a plaited pattern each part of which is composed of curved members. This panel will be made to conform to the shape of the dish to which it is applied. Thus if produced on a circular dish, as in Figs. 2 to 5, inclusive, and Fig. 7, it will be circular. If on an oblong dish, as in Fig. 1, it will be oblong. If on a square or rectangular dish, with or without truncated corners, it will be given 45 similar shape. This central panel is surrounded by a border, B, preferably corresponding in form with that of the panel, which border is made up of a representation of hammered metal, and may or not have the additional 50 ornaments 2, or any other, as may be desired. Such border is, however, only claimed herein

as combined with other elements of this design; but it is to be observed that it may border a plain panel. The edge-border C is made up of sinuous lines, forming a coral-like pattern and producing the ornamental effect shown; and it may or not have associated with it the line of dots 3, as shown. The central pattern or panel, A, may alone be used, as 55 may also the edge-border C.

This design and its segregable parts may be used in connection with deep dishes as well as shallow ones, and may be applied to covered as well as to uncovered dishes. In covered dishes the embodiment of the design will not differ 60 materially from the application of it shown in the flat dishes, Figs. 1, 2, 3, and 4. In the case of the cup, (see Fig. 5,) the edge-border C follows the upper edge of the cup, and the border B follows the lower edge of the cup, the bottom of the cup taking the place of the central panel, A. In the case of the covered dishes, Figs. 6 and 7, the embodiment of the design 65 in the covers is not materially changed. In the bodies of the dishes, however, the border 70 C follows the upper edge and the border B follows the lower edge, and with the latter is combined a portion of the pattern A. The border-patterns A and B might be substituted 75 one for the other, if desired.

The several elements may, singly or wholly, be beautified by coloring one or more of them, and any decoration, as the flowers shown or a similar beautification, may be added to it without materially changing it.

The design embraced in the handles herein shown and described is not claimed herein, as the same forms the subject-matter of a companion application, No. 148,262, filed November 18, 1884.

What is claimed is—

1. The design for dishes, consisting of the central panel, A, representing plaited work made up of curved members, its surrounding border B, representing hammered work, and the edge-border C, constituted by the sinuous coral-like pattern, as shown and described.
2. The design for dishes, consisting of the central panel, A, representing plaited work made up of curved members, as shown and described.
3. The design for dishes, consisting of the

central panel, A, representing plaited work, and its surrounding border B, representing hammered work, as shown and described.

4. The design for dishes, consisting in the edge-border C, composed of a sinuous coral-like pattern, as shown and described.

5. The design for dishes, consisting in the edge-border C, composed of a sinuous coral-like pattern and dots, as shown and described.

6. The design for dishes, consisting of the border B, representing hammered work, and the edge-border C, of a sinuous coral-like pattern, as shown and described.

7. The design for dishes, consisting in the border B, representing hammered work, and the additional ornaments 2, as shown and described.

In testimony whereof I have hereunto set my hand in the presence of two subscribing witnesses.

CHARLES EDWARD HAVILAND.
